CLAIM

USPC D24/155, 156; 606/60, 61, 73, 95, 213,
606/65, 67, 288, 902, 246, 248, 249;
623/17.11, 17.12, 17.13, 17.14, 17.15,
623/17.16, 23.61, 23.56, 247, 213;
D15/143, 139

The ornamental design for spinal fusion implant, substantially as shown and described.

DESCRIPTION

See application file for complete search history.

(56) **References Cited**

FIG. 1 is a perspective view of a spinal fusion implant showing our new design;

U.S. PATENT DOCUMENTS

FIG. 2 is an end view of the leading side of the spinal fusion implant of FIG. 1;

3,486,505 A	12/1969	Morrison
3,518,993 A	7/1970	Blake
3,604,487 A	9/1971	Gilbert
3,745,995 A	7/1973	Kraus
3,848,601 A	11/1974	Ma et al.
4,026,304 A	5/1977	Levy
4,026,305 A	5/1977	Brownlee et al.
4,646,738 A	3/1987	Trott

FIG. 3 is a side view of the spinal fusion implant of FIG. 1; and,

FIG. 4 is an end of the trailing side of the spinal fusion implant of FIG. 1.

The broken line showing is included for the purpose of illustrating portions of the spinal fusion implant that form no part of the claimed design.

1 Claim, 4 Drawing Sheets
